UNITED STATES PATENT OFFICE

ESMOND P. G. WRIGHT, OF ALDWYCH, LONDON, ENGLAND, ASSIGNOR TO WESTERN ELECTRIC COMPANY, INCORPORATED, OF NEW YORK, N. Y., A CORPORATION OF NEW YORK

TELEPHONE EXCHANGE SYSTEM

Application filed May 10, 1929, Serial No. 361,912, and in Great Britain September 5, 1928.

This invention relates to automatic or semi-automatic telephone systems. The object of this invention is to provide a trunking arrangement utilizing a Strowger switch, by means of which the sizes of the groups of trunks terminating in the banks of such switch may be varied to any desired extent within the total capacity of the switch whereby greater economy in the use of the contacts of the switch is effected and more efficient grouping of trunks is realized.

When two-coordinate switches are employed in such systems, particularly when switches are used having contacts arranged in levels so that the brushes of a switch are first moved to select a level and then a contact in that level, the arrangement of lines in groups becomes very inflexible. For example in the Strowger system groups are practically limited to ten trunks each, although traffic requirements may only necessitate fewer trunks than ten in one group, and more trunks than ten in another group. Arrangements have been devised by which there may be twenty trunks in a group, by the use of more than one set of brushes. In this case either all groups must consist of twenty trunks, or contacts of groups not amounting to twenty be wasted.

Arrangements are also known in which a group of lines leading to a private branch exchange may be of any desired size, but these arrangements are applicable only to selector switches in an end stage in a train of selectors. They are, however, inapplicable to the arrangement of trunk lines connecting switches in earlier stages of a system because the time taken to hunt successively over a number of contacts greater than ten, is greater than the time elapsing between the dialing of successive digits.

According to the present invention a selector switch is provided which is capable of use at any switching stage of a system in which a group of trunk lines terminates in more than one level, provision being made for simultaneously testing for an idle trunk in two levels.

In the embodiment of the invention chosen for the purpose of illustration a group selec-

tor switch of the Strowger type having ten levels of ten contacts each having access to ten groups of trunks is provided. Certain groups, however, do not occupy the whole of a level. After a group occupying part of a level, a set of contacts is left spare for a purpose later to be described but the remaining contacts are utilized as overflow contacts from a group or groups on another level. There need be no restriction as to the level on which these overflow contacts appear and they may be distributed over more than one level. These overflow contacts may be either contiguous or non-contiguous to the level in which the main group of contacts terminate.

To a group of such selector switches is multiplied a control circuit hereinafter called a controller containing the relays for controlling the motion of the switch. The controller comprises a selector switch of the same kind mechanically as that first mentioned, which controller may be temporarily associated with an idle one of the selector switches upon seizure of a selector switch. The brushes of the controller and associated selector switch are stepped vertically in unison in response to impulses dialed and are then stepped in rotary hunting movements. The overflow contacts of a group appearing in a level of the selector are connected also to contacts of the controller switch on a level corresponding to that of the main switch in which the main trunks of the group appear.

If the selector is positioned to select a trunk group for which there are no overflow trunks the selector switch alone hunts for a free trunk line and the controller switch which was positioned in unison with the selector switch is stepped in a rotary direction to the end of the particular bank level to which it has been stepped vertically without effect, and on such line being found the connection is extended thereto and the controller switch released. If the selected group possesses overflow contacts both switches are set into motion to hunt for a free trunk line, the selector switch in the main group of trunks and the controller switch in the overflow group.

If the selector switch finds a free outlet

the controller switch is immediately released. If the selector switch fails to find a free outlet and the controller switch finds a free outlet the connection is switched through to the line found over brushes of the controller switch. The next set of impulses dialed may then control the selected switch in the next switching stage, the pulsing circuit extending over the brushes of the controller switch. The release magnet of the selector switch is then energized to release that switch but the circuit thereof remains connected to the controller circuit. The controller also includes a small switch of ten contact sets and having two banks and brushes. Its contacts are connected to contacts of two extra levels of the controller switch, the brushes of which are connected to ground. The vertical magnet of the selector switch and the stepping magnet of this small switch are then energized in a series of steps until the small switch reaches a point marked by the vertical position of the controller switch. The small switch is then returned to normal and the rotary magnet of the selector switch and the magnet of the small switch are energized in a series of steps until the contact corresponding to the level contact on which the controller switch is resting, is reached. The connection is then switched through over brushes of the selector switch and the controller is released.

Referring to the drawings in which one embodiment of the invention has been disclosed, Fig. 1 shows a selector switch and Fig. 2 shows a controlling mechanism common to a group of selector switches such as are disclosed in Fig. 1.

The selector switch 100 of Fig. 1 and the controller selector 200 of Fig. 2 are of a modified Strowger type, each adapted to be stepped vertically in a directive movement and to hunt in a rotary movement. The auxiliary or pilot switch 250 of Fig. 2 is a rotary stepping switch. In general the operation of the selector 100 under the control of the common controller of Fig. 2 is in accordance with the method of operation fully set forth in the application of E. P. G. Wright, J. H. E. Baker, and A. H. Cameron, Serial No. 276,734, filed May 10, 1928. In the following description which may be referred to for a more complete understanding of the invention, each relay has been designated by a letter or numeral and each armature or movable contact of each such relay by a suffix numeral. For example, in tracing a circuit closed through the upper middle contacts of relay H these relay contacts will be referred to as H-4 back, if the relay H is at the time deenergized and, H-4 front, if it is at the time energized.

It will be assumed that a connection has been extended by any well known type of selector, for example such as is shown in the Patent No. 1,580,929 issued to R. L. Stokely

April 13, 1926, to the selector 100 over the trunk conductors 101, 102 and 103 and that both the selector and the common controller of Fig. 2 are at the time idle as will be indicated by the presence of low resistance battery on the test conductor 103. A circuit will therupon be established from ground at the preceding selector over conductor 103, H-2, primary off-normal springs PON-3 of selector 100, the lower winding of relay K, conductor 104 to battery, through the lower winding of relay 2 and in parallel therewith from conductor 104, over primary off-normal springs PNC-3 of controller selector 200, off-normal springs AN-2 of auxiliary switch 250 to battery through the contact 2-2 and the upper non-inductive winding of relay 2. Relays K and 2 operate in this circuit, relay 2 removing its non-inductive winding from the test circuit to mark the selector 100 and controller as busy to other selectors having access to them.

A circuit is now effective for the pulsing of relay 1 extending from battery, contacts 5-4 normal, winding of relay 1, contacts P-4 back, conductor 105, contacts K-10, contacts H-5 normal, conductor 101, over the dialing loop, returning over conductor 102, contacts H-6 normal, contacts K-11, conductor 106, contacts P-5 back to ground. Relay 1 energizes and closes a circuit for slow releasing relay 9 extending from battery, through the winding of relay 9, contacts 1-1 front to ground at contacts P-2. Relay 9 upon energizing closes a holding circuit for relays 2 and K from battery through the lower winding of relay 2, conductor 104, the lower winding of relay K, contact K-3 front, conductor 107 to ground at contacts 9-3, and connects ground from conductor 107, over contacts K-2, thence as previously traced to the test conductor 103.

Relay 1 responds to impulses transmitted over the dialing loop and completes circuits for the vertical magnet V1 of selector 100 and for the vertical magnet V2 of selector 200. The circuit of magnet V1 extends from battery, through the winding of the magnet, contacts K-4, conductor 108, contacts 9-4 front, contacts 5-3 to ground at contacts 1-2. The circuit of magnet V2 extends from battery, through the winding of magnet V2, winding of slow-releasing relay 3, off-normal springs PNC-2, contacts 5-1, contacts 9-1, contacts 1-1 back, contacts P-2 to ground. Relay 3 energizes upon the first impulse and being slow to release remains energized until the train of impulses ceases, and closes an alternate path for itself and magnet V2, extending over its contact 3-1, the initial path being opened at the off-normal springs PNC-2 when the selector 200 steps one step vertically. Relay 3 at its contact 3-3 front also completes an obvious circuit for relay 6 which upon energizing locks

over its winding and contacts 6-2 front, conductor 109, contacts K-8, primary off-normal springs PON-2, the selector 100 having now moved vertically from normal 5 in response to the operation of magnet V1, thence through the interrupter springs of rotary magnet R1, contacts H-3, contacts K-9, conductor 110, contacts 6-4 to ground. Relay 3 also completes a circuit for relay 7 10 from battery, through the winding of relay 7, off-normal springs PNC-4, interrupter springs of rotary magnet R2, contacts 3-2 front to ground. Relay 7 locks over the circuit just traced to ground at its contacts 7-2 15 independent of relay 3.

At the end of the train of impulses relay 3 releases and the brushes of selector 100 are stepped in a rotary direction by the energization of magnet R1 in a circuit extending from 20 battery, winding of magnet R1, contacts K-6, conductor 111, contacts 6-1, contacts 3-3 back to ground. As soon as selector 100 takes one rotary step the circuit of relay 6 is opened. If the first line in the selected 25 level is busy, relay 4 energizes over a circuit extending from battery, through the winding of relay 4, contacts 6-2 back, conductor 109, contacts K-8, off-normal springs PON-2, interrupter springs of magnet R1, eleventh 30 step springs S-1, contacts H-4 back, test brush 112, and the test terminal of the busy trunk to ground. Relay 4 upon energizing again establishes the circuit of rotary magnet R1, extending as previously traced to conductor 111, thence over contacts 4-1 to 35 ground at contacts 3-3 back. Relay 4 maintains itself energized until the interrupter springs of magnet R1 open over a circuit which may be traced from battery, through 40 the winding of relay 4, thence as previously traced to springs PON-2, the interrupter springs of magnet R1, contacts H-3, contacts K-9, conductor 110, to ground at contacts 4-2. Relay 4 and magnet R1 thus 45 operates reciprocally until the test brush 112 encounters an idle trunk terminal.

In the meantime a circuit is closed for the rotary magnet R2 of the selector 200 extending from battery, through the magnet R2, contacts 7-1, contacts 3-2 back to ground. The energization of magnet R2 opens the 50 circuit of relay 7 which thereupon deenergizes. It will first be assumed that the selector 100 has been stepped vertically to the bank level, all the terminals of which constitute a single complete trunk group, for example, to the second level. In this case the test contacts of the second level of the 55 upper bank of the controller selector 200 will be artificially busied by ground connected thereto and when the magnet R2 has rotated the selector shaft one step, a circuit for relay 7 will be established from battery, through the winding of relay 7, off-normal springs 60 PNC-4, interrupter springs of rotary mag-

net R2, rotary eleventh step springs CS-3, contacts O-4 back, brush 201 to ground on the strapped bank terminals with which brush 201 cooperates. Relay 7 again establishes the previously traced circuit for 70 magnet R2 and thereupon magnet R2 and relay 7 interact to rotate the brushes 200 into their eleventh rotary step position where the circuit of relay 7 is opened at the springs CS-3 and the further stepping of the selector is arrested. 75

The selector 100 has in the meantime stepped in a hunting movement in search for an idle trunk terminating in its second bank level. During this stepping a circuit 80 extends from battery, through the winding of relay 4, contacts 6-2 back, conductor 109, contacts K-8 off-normal springs PON-2 interrupter springs of magnet R1, springs S-1, upper winding of relay H, springs 85 S-2, contacts K-2 to ground on conductor 107. As long, however, as ground is encountered by the test brush 112 testing busy trunks, the upper winding of relay H is short-circuited. When, however, an idle trunk is 90 found relay H energizes but relay 4 is unable to energize in series therewith. At its contacts H-5 and H-6 relay H connects the trunk conductors 101 and 102 through to the brushes 113 and 114 of the selector 100 and 95 opens the previously traced pulsing circuit to the winding of relay 1. Relay 1 thereupon releases followed by the release of relay 9. Relay 9 upon deenergizing, opens the holding circuit of relays K and 2. When relay 100 2 deenergizes a circuit for release magnet Z2 of the controller selector 200 is established from battery through the winding of magnet Z2, off-normal springs PNC-1, to ground at contacts 2-1, and the controller 105 selector is restored to normal and may be taken for use by another selector circuit in the same manner as previously described. Following the release of relay K relay H is maintained energized over a circuit extending from battery, through its lower winding, contacts K-9 normal, springs PON-2, interrupter springs of magnet R1, springs S-1, upper winding of relay H, contacts H-4 front, test brush 112 to ground 110 at the succeeding selector. 115

Had selector 100 hunted to the end of the bank level without finding an idle trunk, then the eleventh rotary step springs S would have operated, closing a circuit for relay 5 120 extending from battery, through the winding of relay 5, conductor 115, the eleventh terminal in the second level of selector 100, test brush 112, contacts H-4 back, to ground at springs S-1. Relay 5 upon operating, 125 at its contacts 5-4 transfers the winding of relay 1 from battery through resistance to battery through the primary of tone coil 202 whereupon the calling subscriber receives a busy tone indicating that the call cannot be 130

completed. The calling subscriber then hangs up releasing relay 1 which in turn releases relays 9, 2 and K. With relay H deenergized a circuit is established for restoring selector 100, extending from battery, through the winding of release magnet Z1, off-normal springs PON-1, contacts K-1 back, contacts H-1 to ground. Upon the deenergization of relay 2, the control selector 200 restores in the manner previously described.

It may not be necessary in view of light traffic requirements to provide ten trunks in a trunk group and consequently it does not become necessary to utilize an entire bank 15 level of selector 100 for such a trunk group. In that case a set of bank terminals at the end of such a group is left blank. For example, it will now be assumed that the selectors 100 and 200 have been positioned to their 20 ninth bank levels and that as previously described the selector 100 hunts for an idle trunk terminating in this level. If an idle trunk is found it is seized in the manner previously described. If no idle trunk is found 25 selector 100 rotates its brushes to the blank set of terminals before mentioned whereupon since there is no busy ground on the test terminal, relay H operates and establishes a circuit for relay 5 from battery, winding of 30 relay 5, conductor 115, terminal 116, brush 112, contacts H-4 front, springs S-2, contacts K-2, conductor 107, to ground at contacts 9-3. Relay 5 operates causing the 35 transmission of a busy tone to the calling subscriber indicative that the connection cannot be completed. The calling subscriber then restores all operated apparatus in the manner previously described.

In certain cases it may be desirable in order to handle heavy traffic to provide more trunks in a trunk group than can be terminated in a single bank level of the selector 100. For example, a trunk group terminating in the sixth level of selector 100 may require trunks in addition to the ten which may be terminated in this level and since there are three unused sets of terminals in the ninth level of the selector, a trunk group of thirteen trunks may be obtained by using these three additional sets of terminals as an overflow group. To enable this to be accomplished the tip and ring conductors terminating in the eighth, ninth and tenth sets of terminals in the ninth level of the lower bank of selector 100 are multiplied respectively to the first three sets of terminals in the sixth level of the lower bank of controller selector 200. One of these trunks 117, 118 has been illustrated as so multiplied over conductors 119 and 120. Also the sleeve conductors of these three trunks terminating in the eighth, ninth and tenth terminals of the ninth level of the upper bank of selector 100 have been shown as multiplied to the first three terminal sets 45 in the sixth level of the upper bank of con-

troller selector 200, over conductors 121, 122 and 123.

It will be assumed that a digit is dialed to set both the selector 100 and the controller selector 200 opposite their sixth bank levels and that thereafter both selectors start to rotate in their hunting movements in the manner previously described. The controller selector does not, however, rotate automatically over the entire sixth bank level to its eleventh rotary step position as was the case when it was set to its second bank level as previously described but hunts step by step in search of an idle trunk of the overflow group terminating in the first three sets of terminals of this level. If the first trunk in the overflow group is busy, there will be ground potential on conductor 123 connected to the first test terminal of the sixth level of the upper bank of selector 200 and when the test brush 201 makes contact therewith upon the first rotary step of selector 200, the circuit of relay 7 is established from battery, through the winding of relay 7, off-normal springs PNC-4, interrupter springs of rotary magnet R2, springs CS-3, contacts O-4 back, brush 201 to ground, thereupon again closing the circuit of rotary magnet R2 to advance the selector 200 another step. If the next overflow trunk of the group is also busy, ground potential will be connected over conductor 122 to the next test terminal in the sixth bank level of the selector 200 and the selector will be caused to advance a further step. As long as busy trunks are encountered, relay O cannot operate as it is shunted by ground at test brush 201 connected over a circuit extending through contacts O-4 back, the winding of relay O, springs CS-2, contacts 9-6, contacts 6-3 back to ground at contacts 3-2 back. As soon as an idle trunk is encountered, however, the shunt about relay O is removed at brush 201, and relay O energizes in a circuit extending from battery, through the winding of relay 7, thence as traced through the winding of relay O to ground at contacts 3-2 back. Relay 7 cannot, however, energize in series with relay O.

In the meantime the selector 100 has been hunting for an idle trunk in the main portion of the trunk group, the trunks of which terminate in the sixth level of the banks of selector 100. If the selector 100 has found an idle trunk, relay H operates in the manner previously described thereby releasing the controller selector 200. If, however, the selector does not find an idle trunk, it rotates to its eleventh rotary step position, operating springs S and with relay O operated a circuit is established for relay P extending from battery, winding of relay P, contacts O-1, springs CS-1, conductor 124 to ground at springs S-3. Relay P upon energizing opens the circuit of relay 9 but be-

fore relay 9 has time to deenergize a circuit is closed for releasing selector 100, extending from battery, through the winding of release magnet Z1, off-normal springs PON-1, contacts K-1 front, conductor 125, contacts P-6, contacts 9-2 to ground. The brushes of selector 100 are thereby restored to normal but the incoming trunk conductors 101, 102 are connected respectively over contacts 10 H-5 normal, contacts K-10, conductor 105, contacts P-4 front to brush 203 and over contacts H-6 normal, contacts K-11, conductor 106, contacts P-5 front to brush 204 of controller selector 200, thence to the 15 tip and ring contacts of the overflow trunk which has been seized by the selector 200. This by-pass connection over the brushes of selector 200 enables the continuation of dialing to set the succeeding selector without the 20 loss of impulses.

Relay P upon energizing also locks over a circuit extending through its winding, contacts P-1, to ground at contacts 2-3 front and relay O locks in series with the winding 25 of relay 7, over its contact O-4 front, brush 201 to ground at the seized selector. At contacts O-2 a circuit for holding relays 2 and K operated is closed extending from conductor 107, contacts O-2, conductor 126, 30 contacts K-12, contacts H-1 to ground. Circuits are now established for repositioning the selector 100 into a position in which a connection may be made to the terminals of the trunk appearing in the ninth level 35 of its banks which has been seized over multiples thereof by the controller selector 200, that is, for stepping the selector 100 to the tenth set of terminals in its ninth bank level.

To accomplish this a circuit is closed from 40 battery, through the winding of stepping magnet SM of the auxiliary switch 250, contacts Y-3 back, contacts 8-2, contacts 9-4 back, conductor 108, contacts K-4, and in parallel therewith to battery through the 45 vertical magnet V1 of selector 100, thence over the interrupter springs of magnet V1, contacts K-5, conductor 127, contacts O-3, contacts 9-5, contacts 8-4 back to ground at contacts Y-6 back. Each magnet causes 50 its brushes to be advanced a step, the magnet V1 opening the stepping circuit at its interrupter springs. In this manner the selector 100 is stepped vertically step by step in unison with the stepping of switch 250 until 55 the brush S-1 of switch 250 encounters a terminal of its bank which is connected to a terminal of the level to which the brushes of the selector 200 have been raised to connect with the idle overflow trunk. This terminal 60 has been assumed to be in the third terminal set of the sixth level. Thereupon a circuit is closed for relay 8, extending from battery, through the winding of relay 8, contacts Y-5 back, brush S-1 of switch 250 and the ninth terminal of its arc, conductor

205, terminal 206, brush 207 to ground. Relay 8 upon energizing opens the previously traced circuits of magnets SM and V1 arresting the further advance of the selector 100 and switch 250. The brushes of selector 100 have now been positioned opposite the ninth level of bank terminals in which the overflow trunks appear.

Relay 8 upon energizing locks over its contact 8-3, contacts 2-4 to ground at contacts Y-2 until relay Y energizes and at its contacts 8-1 closes a circuit extending from battery, through the lower winding of relay Y, contacts Y-1, contacts 8-1, off-normal springs AN-1 of switch 250 to ground. Relay Y upon energizing at this time operates only its contacts 2 and thereby closes a locking circuit for itself extending from battery through its two windings, contacts Y-2, contacts 2-3 front to ground. Since relay 8 is still operated, however, the upper winding of relay Y is short-circuited and ineffective. A circuit is now closed for restoring the auxiliary switch 250 which may be traced from battery, through the winding of magnet SM, interrupter springs of magnet SM, springs AN-3, contacts 8-4 front, contacts Y-6 back to ground. As soon as the auxiliary switch reaches normal this stepping circuit is opened at off-normal springs AN-3 and the short-circuit around the upper winding of relay Y now being opened at off-normal springs AN-1, relay Y fully energizes opening the circuit of relay 8 which then releases.

A circuit is now closed for relay 4 from battery, through the winding of that relay, contacts 6-2 back, conductor 109, contacts K-8, off-normal springs PON-2, interrupter springs of magnet R1, contacts H-3, contacts K-9, conductor 110, contacts 8-5 back, contacts Y-6 front to ground. Relay 4 energizes closing at its contacts 4-1 a circuit for magnet R1 extending from battery, through the winding of magnet R1, contacts K-6, conductor 111, contacts 4-1, contacts 3-3 back to ground and at its contacts 4-3 closing a circuit for magnet SM, extending from battery, through the winding of magnet SM, contacts Y-3 front, contacts 4-3 to ground. Upon the first step of selector 100, in response to the operation of magnet R1, the circuit of relay 4 is opened at the interrupter springs of magnet R1 and relay 4 deenergizes, opening the circuits of magnets R1 and SM. In this manner relay 4 and magnets R1 and SM reciprocally control each other until the brush S2 of switch 250 is positioned upon a terminal connected with a terminal of selector 200 to which the brushes of that selector have been rotated to connect with the idle overflow trunk. This terminal has been assumed to be in the third terminal set of the sixth level.

A circuit is thereupon closed for relay 8

extending from battery, through the winding of relay 8, contacts Y-5 front, brush S2 and the tenth terminal of the arc with which it cooperates, conductor 208, terminal 209, to ground on brush 210. Relay 8 thereupon energizes and at its contacts 8-5 opens the circuit of relay 4 to prevent further stepping of the selector 100 and of the switch 250. At this time the selector 100 has stepped its 10 brushes into engagement with the tenth set of terminals in its ninth bank level which it will be recalled are multiplied to terminals in the sixth level of the selector 200 upon which brushes of selector 200 are now resting.

15 With both relays 8 and Y now energized, a circuit is established for relay H of selector 100 extending from battery, through the lower winding of relay H, contacts K-7, conductor 128, contacts 8-5 front, contacts Y-6 front 20 to ground. The operation of relay H connects the incoming trunk conductors 101 and 102 through to the tip and ring brushes 113 and 114 of selector 100 in a manner previously described whereupon the dialing circuit over contacts 101 and 102 is extended directly to the overflow trunk previously selected by controller selector 200. Relay H also causes the release of relays 1 and 2 followed by the release of relay 9 in the manner 25 previously described. Upon the release of relay 2 the holding circuits of relays P, Y and 8 are opened and these relays release. The release of relay 2 also causes the release of selector 200 in the manner described and the release of switch 250 in a circuit extending from battery, through the winding and interrupter springs of magnet SM, off-normal springs A-3 to ground at springs 2-3 back. When the switch 250 reaches normal, the circuit of magnet SM is opened at off-normal springs AN-3.

40 The overflow group of trunks need not be confined to a single level of selector 100 but may, as illustrated, comprise trunks terminating in terminals of more than one level. For example, in addition to the trunks terminating in the ninth level of selector 100 other trunks serving as overflow trunks may also terminate in the eighth, ninth, and tenth terminal 45 sets of the fourth level of selector 100. These trunks are also multiplied to the fourth, fifth and sixth terminal sets in the sixth level of the banks of controller selector 200. Thus if the selector 200 in hunting for an idle overflow trunk at the time selector 100 hunts for an idle trunk in the main group, fails to find an idle overflow trunk among the three trunks multiplied to the first three terminal 50 sets in its sixth level, it will continue to hunt over succeeding terminals and if it finds an idle trunk, for example, the trunk multiplied to the fourth terminal set and to the eighth terminal set of the fourth level of selector 100, it will seize such overflow trunk in

the manner previously described whereupon the selector 100 is released and is then reset under the control of switch 250 to connect with the multiple of the overflow trunk appearing in the eighth terminal set of its fourth bank level.

If the overflow trunk multiples do not occupy a full level of the controller selector, the excess terminals are rendered artificially busy by the connection to ground of the test terminals to which the test brush 201 has access. Thus if the controller selector hunts over all trunk terminals of an overflow group and fails to find an idle trunk, it steps automatically over the remaining portion of the level until the eleventh step rotary springs CS are operated. If also the selector 100 has found no idle trunk in the main group, the springs S of such selector will also be operated and a circuit will thereupon be established for relay 5 extending from battery, through the winding of relay 5, springs CS-1, conductor 124 to ground at springs S-3. Relay 5 upon energizing causes the transmission of a busy tone to the calling subscriber's line in the manner previously described whereupon the subscriber initiates the release of all operated apparatus.

What is claimed is:

1. In a telephone system, two switches, each having operating magnets individual thereto, means actuated in accordance with part of the designation of a desired line to cause both switches to hunt simultaneously for a free line within different portions of the same group of lines and means for extending the connection over brushes of either of said switches.

2. In a telephone system, two switches, means actuated in accordance with part of the designation of a desired line to cause both switches to hunt simultaneously for a free line within different portions of the same group of lines, means for extending the connection over brushes of either of said switches, means operative if a connection is established over brushes of one of said switches to reset the other of said switches to the line seized by said one switch, and means for thereupon releasing said one switch.

3. In a telephone system, a selector switch, means for actuating the switch in one manner in accordance with part of the numerical designation of a desired line to select a group of trunks, a second switch, means for actuating the second switch in the same manner as and simultaneously with the first switch, and discriminating means actuated in accordance with the size of the group selected by the first switch to determine that either the first switch or both switches shall be actuated in another manner to select a free trunk within said group of trunks.

4. In a telephone system, a selector switch, means for actuating the switch in one manner

in accordance with part of a numerical designation of a desired line to select a group of trunks, a second switch adapted upon seizing a free trunk to extend the connection thereto over its own brushes, means for completing such connection only after the first switch has tested all trunks immediately accessible thereto, means for actuating the second switch in the same manner as and simultaneously with the first switch, and discriminating means actuated in accordance with the size of the group selected by the first switch to determine that either the first switch or both switches shall be actuated in any manner to select a free trunk within said group of trunks.

5. In a telephone system, a two-motion switch, means to cause said switch to select a group of lines, means to cause said switch to hunt for a free line in a portion of said group of lines, a second switch, means for moving said second switch simultaneously with the first motion of the first switch and thereafter in a hunting movement to hunt for a free line in another portion of said group, and means to cause further selecting motions of the first switch to the line in said other portion of said group selected by said second switch if all lines in the first portion of said group are found busy, said means comprising means for marking the amount of such further motion in accordance with the movements of the second switch.

6. In a telephone system, a plurality of selector switches, a control switch common thereto, means for rendering the control switch temporarily individual to one of the selector switches, means for stepping both switches in accordance with impulses representing part of the designation of a wanted line, means for thereupon causing one switch to hunt for a free line within one portion of a group of lines and for causing the other switch to hunt for a free line within another portion of the same group, means responsive to the finding of a free line by the control switch for positioning the associated selector switch upon contacts of the said line, and means for thereupon releasing the control switch.

7. In a telephone system, in combination, groups of trunks, a plurality of selector switches, a second switch common to said selector switches, means for actuating the second switch in accordance with part of the designation of a wanted line, means for extending a connection over brushes and contacts of the said second switch to an idle trunk in a desired one of said groups of trunks, means for thereupon positioning one of said selector switches upon contacts of the trunk selected by the said second switch, means for extending the connection over brushes of the said selector switch to the selected trunk, and

means for thereupon releasing the said second switch.

8. In a telephone system, the combination of a first switch, a second switch, a group of lines of which some are connected to contacts of both said switches, means for stepping the brushes of the second switch to a particular level and for then rotating said brushes in that level in search for an idle line, a third switch contacts on the said level of the second switch connected to contacts of said third switch, means for moving the first switch and the third switch simultaneously, and means for stopping both switches when the said third switch reaches a contact connected to a contact of the second switch corresponding to the level in said first switch of the line selected at said second switch.

9. In a telephone system, the combination of a first switch, a second switch, a group of lines of which some are connected to contacts of both said switches, means for stepping the brushes of the second switch to a particular level and for then rotating said brushes in that level in search for an idle line, a third switch, means for stepping said third switch to a position indicated by the level to which said second switch has been stepped, means for stepping said first switch vertically in unison with said third switch to select a level therein in which said idle line appears, means for then restoring said third switch, means for resetting said third switch to a position indicated by the contact in the selected level to which said second switch has been stepped, and means for rotating said first switch in unison with said third switch to select a contact in which said line appears therein.

10. In a telephone system, a switch having a plurality of groups of lines terminating in the bank levels thereof, means actuated in accordance with part of the designation of a desired line to cause said switch to select a bank level in which a line group terminates, a second switch operable in unison therewith to select a corresponding bank level thereof, means for causing both of said switches to hunt in selected bank levels and means effective if a line group terminates only in a single bank level of said first switch for causing the hunting operation of said first switch to seize an idle line and for rendering the hunting operation of said second switch ineffective.

11. In a telephone system, a switch having a plurality of groups of lines terminating in the bank levels thereof, means actuated in accordance with part of the designation of a desired line to cause said switch to select a bank level in which a line group terminates, a second switch operable in unison therewith to select a corresponding bank level thereof, means for causing both of said switches to hunt in selected bank levels, and means effective if a line group terminates in a portion

only of a single bank level of said first switch for causing the hunting operation of said first switch to seize an idle line and for rendering the hunting operation of said second switch ineffective.

12. In a telephone system, a switch, a group of lines divided into a main subgroup and an overflow subgroup, said main subgroup of lines terminating in a single bank level of said switch and the lines of said overflow subgroup being dispersed into a plurality of other bank levels of said switch, a second switch in which the lines of said overflow subgroup are multiplied to bank contacts of a level corresponding to the level of said first switch in which the main subgroup of lines terminates, and means actuated in accordance with part of the designation of a desired line to cause said switches to step in unison to select levels in which said lines terminate and to hunt for an idle line.

13. In a telephone system, a switch, a group of lines divided into a main subgroup and an overflow subgroup, said main subgroup of lines terminating in a single bank level of said switch and the lines of said overflow subgroup being dispersed into a plurality of other bank levels of said switch, a second switch in which the lines of said overflow subgroup are multiplied to bank contacts of a level corresponding to the level of said first switch in which the main subgroup of lines terminates, means actuated in accordance with part of the designation of a desired line to cause said switches to step in unison to select levels in which said lines terminate and to hunt for an idle line, and means for rendering the operation of said second switch ineffective if said first switch finds an idle line in the main subgroup.

14. In a telephone system, a switch, a group of lines divided into a main subgroup and an overflow subgroup, said main subgroup of lines terminating in a single bank level of said switch and the lines of said overflow subgroup being dispersed into a plurality of other bank levels of said switch, a second switch in which the lines of said overflow subgroup are multiplied to bank contacts of a level corresponding to the level of said first switch in which the main subgroup of lines terminates, means actuated in accordance with part of the designation of a desired line to cause said switches to step in unison to select levels in which said lines terminate and to hunt for an idle line, means for rendering the operation of said second switch ineffective if said first switch finds an idle line in the main subgroup, and means for restoring and resetting said first switch to the level in which an idle overflow line terminates if in hunting it finds no idle line in said main subgroup and said second switch finds an idle line in an overflow subgroup.

15. In a telephone system, a switch, a group

of lines divided into a main subgroup and an overflow subgroup, said main subgroup of lines terminating in a single bank level of said switch and the lines of said overflow subgroup being dispersed into a plurality of other bank levels of said switch, a second switch in which the lines of said overflow subgroup are multiplied to bank contacts of a level corresponding to the level of said first switch in which the main subgroup of lines terminates, means actuated in accordance with part of the designation of a desired line to cause said switches to step in unison to select levels in which said lines terminate and to hunt for an idle line, means for rendering the operation of said second switch ineffective if said first switch finds an idle line in the main subgroup, means for restoring and resetting said first switch to the level in which an idle overflow line terminates if in hunting it finds no idle line in said main subgroup and said second switch finds an idle line in said overflow subgroup, and means for thereafter restoring said second switch.

In witness whereof, I hereunto subscribe my name this 8th day of April, 1929.

ESMOND P. G. WRIGHT.
